(57) **CLAIM**

The ornamental design for an outdoor power post as shown
and described.

DESCRIPTION

FIG. 1 is a perspective view of an outdoor power post
according to the present design;

FIG. 2 is a front view of the outdoor power post of FIG. 1;
FIG. 3 is a rear view of the outdoor power post of FIG. 1;
FIG. 4 is a left side view of the outdoor power post of FIG.
1;

FIG. 5 is a right side view of the outdoor power post of FIG.
1;

FIG. 6 is a top view of the outdoor power post of FIG. 1; and,
FIG. 7 is a bottom view of the outdoor power post of FIG.
1.

In the drawings, the broken lines are for the purpose of
illustrating portions of the outdoor power post that form no
part of the claimed design.

1 Claim, 6 Drawing Sheets
